UNITED STATES PATENT OFFICE

CLARENCE S. KEATING, OF CHICAGO, ILLINOIS

DESIGN FOR A CHEESE SERVETTE

Application filed February 27, 1933. Serial No. 47,339. Term of patent 7 years.

To all whom it may concern:

Be it known that I, CLARENCE S. KEATING, a citizen of the United States, residing at Chicago, Cook County, Illinois, have invented a new, original, and ornamental Design for a Cheese Servette, of which the following is a specification.

The design is shown in the accompanying drawing, which forms a part hereof, and in which:

The cover is of clear glass and the saucer is colored.

I claim:

The ornamental design for a cheese servette substantially as shown and described.

CLARENCE S. KEATING.
